UNITED STATES PATENT OFFICE

ROBERT F. RINGLE, OF ZELIENOPLE, PENNSYLVANIA

MOVEMENT-REGULATING MECHANISM

Application filed March 7, 1928. Serial No. 259,894.

My invention is an improvement in means for controlling the number of movements of a fluid-actuated mechanism, dependent on the regulation of the actuating fluid. It is particularly designed in connection with a bumping machine or the like, for molding flasks, where it is desirable to impart a definite number of movements for each complete operation, or in any machine to which the invention may be applied.

In the drawings showing one application of the invention:

Fig. 1 is a sectional view showing the application of the invention to a bumping machine, with the plunger and valve mechanism in primary position;

Fig. 2 is a detail view on the line II—II of Fig. 1;

Fig. 3 is a plan view of Fig. 1;

Fig. 4 is a sectional view of the plunger and valve mechanism in its secondary position;

Fig. 5 is a similar view in its final valve closing position;

Fig. 6 is a face view of the cam-controlling dial.

In the drawings, a bumping machine A is provided with a supporting base 2 on which is mounted a reciprocable bumping table 3 for flask agitation, of well known construction. In such mechanism it is desirable to impart to the table for each bumping operation a definite number of vibrations.

The bumping machine is operated by a fluid-actuated motor M, as an air motor to which air is supplied by a pipe 4 from a pressure supply pipe 5 through a controlling valve 6. Said valve opens and closes a valve-seated port 7 for circulation through a casing 8 with which pipes 4 and 5 are connected at each side of the port 7. The valve is normally pressed towards the valve seat for closing by a spring 9 seated in a suitable socket or casing 10 and has a projecting stem 11 extending through the top of casing 8.

A trigger arm 12 is secured to pivoting pin 13 mounted in bracket 14 and provided with a re-setting handle 15. The trigger arm 12 is provided at its other end with a shoulder 16 for engagement by the upper end of a trigger

50 17 pivoted at 18 on bracket 14 and having a

lever extension 19 located in the path of plunger pin 20 of fluid-actuated plunger 21. Arm 12 is also provided beyond shoulder 16 with a cam abutment 60. The trigger 17 is normally held in locking position, as in Fig. 1, by spring 22 mounted on bracket 14.

Plunger 21 is gradually advanced in its cylinder casing 23 against retracting spring 24 by impulse of fluid in regulated amounts through ports 25, 26, as flow is admitted by the opening and closing of valve 27. Said valve is normally seated by spring 28 and is opened by impulses of fluid, as oil, from a reservoir 29 through valve-controlled port 30 communicating with port 25 and by port 31 with the plunger cavity 32 of plunger casing 33.

Post 30 is opened and closed by a spring-seated valve 34, closing the port upon upward movement of plunger 35 and opening it upon downward suction movement of the plunger. The plunger 35 is connected by stem 36 with the armature 37 of a solenoid magnet 38, the winding field of which is energized by current from a generator 39 by conductors 40, 41.

The circuit is closed on each upward movement of the table 3 by contacts 42, 43, one of which is on a pivoted arm 44, normally opened by spring re-action and closed by a cam 45 connected with the table, as shown in Fig. 1, or by other suitable means.

For the purpose of regulating the pumping stroke of the plunger 37 an adjustable cam 46 supports the armature at varying heights, dependent on the cam adjustment by rotation of its supporting rod 47. Said rod is carried in bearings 48 depending from casing 33 and is provided at one end with a turning and indicating dial 49 adapted to rotate in the range of a locking device as a set screw 50 of bracket 51. The latter is provided with an aperture 52 and indicating point for observation and indication of range indicating numerals on the dial, as shown in Fig. 6. By such means the location of the cam controls the length of stroke of plunger 35, which is retracted after opening of the circuit at each drop of the table, by spring 53.

For the purpose of returning the oil to tank 100

29 after each advance movement of plunger 21 I provide a valve 54 controlling circulation through port 55 and the valve-seated port leading to return conduit 56, discharging into the reservoir, as shown in Fig. 1. Valve 54 is normally seated by a spring 57 and is provided with an extended stem 58 mounted in an outer bearing 59 of the casing 33, with the end of the stem in range of trigger arm 17.

10 When plunger 21 advances and stem 20 disengages the trigger so as to allow valve 6 to seat and cut off the circulation, the stem 58 will be depressed backwardly by arm 17 under pressure of cam 60 at the end of the 15 plunger stroke, Fig. 4, releasing the oil behind the plunger and allowing spring 24 to force it back to the original position.

The construction and operation of the apparatus will be readily understood from the 20 foregoing description. Dependent upon the position of cam 46, the stroke of plunger 35 will be longer or shorter each time the circuit is closed to the magnet 38 by movement 25 of the table 3. The cam being set to the desired position, to regulate the stroke of the armature and plunger 35, the amount of liquid pumped through valve 27 into the casing 23, and withdrawn from tank 29 through port 30, at each plunger operation, definitely 30 determines the number of strokes necessary to force plunger 21 outwardly sufficiently far to disengage the trigger 12.

After the stem 20 has forced arm 19 sufficiently far to release the trigger as in Fig. 4, 35 the valve 6 will be almost closed by its spring 9, still admitting a limited air supply through pipe 4 to the motor, slowing down the operation. Thereafter additional oil will be pumped into casing 23, the plunger then moving to its outward limit and opening valve 54 for release as in Fig. 5. At such time trigger 12 is thrown upwardly sufficiently far to bring its cam extension 60 fully against the arm 17 and thrusting rod 58 inwardly to fully unseat 45 valve 54, as in Fig. 5.

Partial or complete action of cam abutment 60 will effect such unseating, whereby to empty the casing 23 upon reverse movement of plunger 21.

50 By movement of hand lever 15 the same operation may be effected or completed, and by varying the shape of the lever 12 or the length of the valve pin 11, the thrusting movement of the cam may be varied or adjusted to the desired opening movement of the valve.

The hand lever may also be utilized independently of the plunger movement by manual operation of the trigger, to empty the casing and effect resumption of the parts to normal position.

60 The construction, design, arrangement and proportions of the mechanism may be variously changed or modified as to location of the valve, circulating ports, or in other details

by the skilled mechanic, but all such changes are to be understood as within the scope of the following claims.

What I claim is:

1. Means for regulating movements of the active element of a machine having a fluid-actuated motor consisting of a motor controlling valve, means for closing the valve, means holding the valve open, a fluid-actuated device for releasing the valve, and means controlled by the active element of the machine effecting movement of the fluid-actuated device. 70

2. Means for regulating movements of the active element of a machine having a fluid-actuated motor consisting of a valve controlling flow of fluid to the motor, a spring for closing the valve, an opening lever, a holding trigger therefor, a fluid-actuated device for releasing the trigger, means for supplying fluid pressure to said device, and means controlled by the active element of the machine for imparting movement to said means. 80

3. Means for regulating movements of the active element of a machine having a fluid-actuated motor consisting of a valve controlling flow of fluid to the motor, a spring for closing the valve, an opening lever, a holding trigger therefor, a fluid-actuated device for releasing the trigger, means for supplying fluid pressure to said device, means controlled by the active element of the machine for imparting movement to said means, and means operative upon closing of the valve effecting release of fluid pressure from the trigger releasing device. 90

4. Means for regulating movements of the active element of a machine having a fluid-actuated motor consisting of a valve controlling flow of fluid to the motor, a spring for closing the valve, an opening lever, a holding trigger therefor, a fluid-actuated device for releasing the trigger, means for supplying fluid pressure to said device, means controlled by the active element of the machine for imparting movement to said means, and a release valve for the fluid-actuated device having a stem projecting in the path of the trigger. 105

5. In combination with a bumping machine having a vibrating top and a motor therefor, a fluid supply pipe for the motor, a flow controlling valve therefor, means for closing the valve, trigger controlled mechanism holding the valve open, fluid-actuated releasing mechanism therefor, means for pumping fluid to said mechanism, and a motor therefor controlled by the movement of the bumping machine. 115

6. In combination with a bumping machine having a vibrating top and a motor therefor, a fluid supply pipe for the motor, a flow controlling valve therefor, means for closing the valve, trigger controlled mechanism holding the valve open, fluid-actuated 125

130

releasing mechanism therefor, means for pumping fluid to said mechanism, a motor therefor controlled by the movement of the bumping machine, and a valve for releasing pressure from the fluid-actuated releasing mechanism operable by the trigger mechanism.

7. In combination with a bumping machine having a vibrating top and a motor therefor, a fluid supply pipe for the motor, a flow controlling valve therefor, means for closing the valve, trigger controlled mechanism holding the valve open, fluid-actuated releasing mechanism therefor, means for pumping fluid to said mechanism, a magnet and armature operatively connected with the pumping means, and a controlling circuit therefor having contact mechanism opened and closed at each movement of the bumping machine.

8. In combination with a spring seated controlling valve for fluid supply to the motor of a bumping machine, a valve opening lever having a trigger engaging abutment, a trigger therefor, a plunger casing having a spring retracted plunger and a trigger engaging stem, a releasing valve therefor operable by the trigger, and means for cumulatively pumping fluid to said casing.

30 9. In combination with a spring seated controlling valve for fluid supply to the motor of a bumping machine, a valve opening lever having a trigger engaging abutment, a trigger therefor, a plunger casing having a spring 35 retracted plunger and a trigger engaging stem, a releasing valve therefor operable by the trigger, and means for cumulatively pumping fluid to said casing having an actuating motor controlled by means mounted on the bumping machine.

40 10. In combination with a spring seated controlling valve for fluid supply to the motor of a bumping machine, a valve opening lever having a trigger engaging abutment, a trigger therefor, a plunger casing having a spring 45 retracted plunger and a trigger engaging stem, a releasing valve therefor operable by the trigger, a reciprocable plunger device for cumulatively pumping fluid to said casing 50 having an armature, and a magnet therefor provided with a circuit having opening and closing switch mechanism operating in conformity with the movement of the bumping machine.

55 11. In combination with a valve casing having a spring seated valve controlling circulation of pressure fluid to a reciprocable motor, a valve stem projecting from the casing, a pivoted depressing lever therefor having a trigger abutment, a pivoted trigger therefor, a plunger casing having an inlet port and an exhaust port, a releasing valve controlling flow through the exhaust port having a stem 60 projecting towards the trigger, a spring retracted plunger in the casing having a stem 65

projecting towards the trigger, and means for pumping fluid to the casing.

12. In combination with a valve casing having a spring seated valve controlling circulation of pressure fluid to a reciprocable motor, a valve stem projecting from the casing, a pivoted depressing lever therefor having a trigger abutment and a trigger actuating cam, a pivoted trigger therefor, a plunger casing having an inlet port and an exhaust port, a releasing valve controlling flow through the exhaust port having a stem projecting towards the trigger, a spring retracted plunger in the casing having a stem projecting towards the trigger, and means for pumping fluid to the casing.

70 13. In combination with a plunger casing having a trigger releasing plunger and stem and provided with a fluid exhaust valve, a fluid reservoir having valve controlled supply conduits leading to the casing, a pumping plunger operable to intermittently force fluid therethrough to the casing, means for actuating the plunger, and means providing return flow of fluid through the release valve 75 80 back to the reservoir.

85 14. In combination with a valve casing having a spring seated valve controlling circulation of pressure fluid to a reciprocable motor, a valve stem projecting from the casing, a pivoted depressing lever therefor having a trigger abutment, a pivoted trigger therefor, a plunger casing having an inlet port, and an exhaust port, a releasing valve controlling flow through the exhaust port 90 having a stem projecting towards the trigger, a spring retracted plunger in the casing having a stem projecting towards the trigger, means for pumping fluid to the casing, and a hand lever connected with the depressing lever.

In testimony whereof I hereunto affix my signature.
